UNITED STATES PATENT OFFICE.

WILLIAM H. PALMER, JR., OF WAYNE, PENNSYLVANIA.

COMBINED PACKING CASE AND TRAY FOR STORAGE-BATTERY CELLS.

Application filed July 10, 1926. Serial No. 121,555.

The principal object of the present invention is to provide a structure which when completely assembled forms a satisfactory packing and shipping case, including a 5 peaked top and extended side pieces for facilitating handling and completely enclosing and protecting the cells from mechanical injury and which includes parts arranged to be readily and conveniently removed, leaving 10 other parts in suitable form to act as a permanent tray for the cells, leaving openings on the sides to facilitate inspection and leaving the top exposed for making connections and for filling with electrolyte. Another 15 object of the invention is to provide a composite structure adapted for use as a crate in shipping batteries and readily convertible into a permanent battery tray.

Other objects of the invention will appear 20 from the following description at the end of which the invention will be claimed. However, generally stated, the invention may be said to comprise a combined packing case and tray for storage battery cells comprising a two-part detachable structure of which one part includes a subdivided tray having end walls and slat sides of which the intermediate slats are removable, and of which the other part comprises a housing having 25 a peaked top and side bars of which prolongations constitute handles and ends arranged to overlap the end walls of the tray and adapted for detachable connection therewith, with or without packing felt removable through the spaces between the 30 slats.

In the following description reference will be made to the accompanying drawing forming part hereof and in which

40 Figure 1 is a perspective view of the combined packing case and tray showing the two parts thereof assembled for use as a crate.

Fig. 2 is a similar view showing one of the 45 parts of the combined structure removed leaving the other part for use as a tray.

Fig. 3 is a top or plan view drawn to an enlarged scale with parts broken away.

Fig. 4 is an elevational view of Fig. 3 50 with parts broken away, and

Fig. 5 is an end view.

Referring to the drawing one of the two 55 parts of the detachable structure includes a tray, Fig. 2, subdivided or partitioned as at 3 and having end walls 4 and slat sides

5 of which the intermediate slats 5^a are removable. The other part of the two-part detachable structure comprises the housing, Fig. 1, having a peaked top 6, side bars 7 of which prolongations 8 constitute handles, 60 and ends 9 arranged to overlap the end walls 4 of the tray. 10 are screws by means of which the overlapping walls 4 and 9 are detachably connected, and 12 are screws or like fastenings by which the detachable slats 5^a 65 are connected with the ends and partitions of the tray. 13 are pieces of felt or the like of which one is shown in Fig. 2 as partly removed, and they are placed between the glass jars and the sides of the tray to act 70 as buffers during transportation but they can be readily removed at destination so that the cells can be inspected through openings in the tray provided by the removal of the slats 5^a. 75

For the sake of further description it may be said that Fig. 1 illustrates storage battery cells crated according to my invention for shipment and that Fig. 2 illustrates the same at destination after the parts, generally indicated in white Fig. 1, along with the felt 80 13, have been removed, so that Fig. 2 shows the storage battery cells mounted in the tray adapted to contain them while in service.

From the foregoing description it is evident that a considerable economy is effected 85 by the invention and also it adds convenience.

It will be obvious to those skilled in the art to which the invention relates that modifications may be made in details of construction and arrangement and in matters of mere form without departing from the spirit of the invention which is not limited to such matters or otherwise than the prior 90 art and the appended claims may require. 95

I claim:

1. A combined packing case and tray for storage battery cells comprising a two-part 100 detachable structure of which one part includes a subdivided tray having end walls and slat sides of which the intermediate slats are removable, and of which the other part includes a housing having a peaked top and side bars of which elongations constitute handles and ends arranged in overlapping relation with the end walls of the tray and adapted for detachable connection therewith.

2. A combined packing case and tray for 110

storage battery cells comprising a two-part detachable structure of which one part includes a subdivided tray having end walls and slat sides of which the intermediate slats are removable, and of which the other part includes a housing having a peaked top and side bars of which elongations consti-

tute handles and ends arranged in overlapping relation with the end walls of the tray and adapted for detachable connection therewith, and packing felt removable through the space between the slats.

WILLIAM H. PALMER, JR.
